UNITED STATES PATENT OFFICE.

HENRY L. FERRIS, OF HARVARD, ILLINOIS, ASSIGNOR TO HUNT, HELM & FERRIS, OF SAME PLACE.

FEED-BOX.

SPECIFICATION forming part of Letters Patent No. 598,563, dated February 8, 1898.

Application filed February 13, 1897. Serial No. 623,340. (No model.)

To all whom it may concern:

Be it known that I, HENRY L. FERRIS, a citizen of the United States of America, residing at Harvard, in the county of McHenry and 5 State of Illinois, have invented certain new and useful Improvements in Feed-Boxes, of which the following is a specification.

My invention relates to certain improvements, the aim of which is to produce a feed- 10 box for use in feeding horses or other animals that will minimize the waste feed and will also tend to check the rapid eating of the same, to the end that it may be more thoroughly masticated. In this view I aim to save 15 both in the actual feeding of the animal and in the assimilation of the food after it is eaten.

The drawings show four figures of the preferred form of my feed-box, in which Figure 1 is a front view of the same. Fig. 2 is a vertical section in line 2 2 of Fig. 1. Fig. 3 is a side elevation of the box, and Fig. 4 is a broken perspective designed especially to show the manner of hinging the movable parts of the same.

25 In the drawings, A is a back portion to which the parts of the feed-box proper are secured. Said back portion is provided with a keyhole-shaped opening a, by means of which the back may be hung upon a nail or hook 30 when it is desired to do so. In a great many cases it will be possible to dispense with this back entirely when the feed-box is to be secured against the side of a barn or a partition thereof and to remain in the same place. In 35 such cases any tight wall or partition will obviously answer all the purposes of this back.

The main body portion of the feed-box B is 40 preferably provided with laterally-projecting ears b b' b² b³, which may be secured to the back A or any other tight and substantially flat surface by means of bolts or screws C. Said body portion is here shown as consisting of a rectangular three-sided vertical trough having a front portion b⁴ and side portions b⁵ 45 b⁶, respectively. The shape of the upper portion of this trough is immaterial, being here shown as flat to receive a hinged lid D, which is hinged to the side portions of the box b⁵ b⁶ by means of notches b⁷ b⁸, formed in the rear 50 edges of these side portions and laterally-projecting lugs d, projecting in opposite direc-

tions from the rear portions of the edges of the door. These lugs are dropped into the notches of the sides before the back A is secured to the portion B and are thereafter confined within said notches by said back. 55

The bottom of the box or trough D is preferably inclined downwardly away from the back A, and a hinged bottom E is hinged at the rear of the same by means of lugs b⁹ b¹⁰, 60 extending outwardly and horizontally from the rear of the lower edges of the sides b⁵ b⁶ and by means of hooks e e' upon the rear portion of the bottom E, said hooks being open toward the front of the feed-box and being 65 also placed upon the lugs before the attachment of the back and held in place by said back. The bottom is preferably provided at its sides with upwardly-extending vertical flanges e² e³, embracing the vertical trough or 70 box B, and in front of said box extends downward and forward in the shape of a horizontal trough e⁴, closed at the ends and shaped to enable an animal to eat grain easily and conveniently therefrom. The entire bottom is 75 yieldingly pressed against the bottom of the box B by means of a connecting-bolt F, here secured in the front of said box and extending therefrom at an angle through the hinged bottom in a line which is preferably substantially normal thereto. Below the bottom the bolt is provided with a nut f, between which and the under side of a bottom is a coiled spring G. The pressure of said spring upon the bottom tends to hold it against the box, 80 and said pressure may be varied and the limit of motion of the bottom changed as desired by the adjustment of the nut upon the end of the bolt. At the bottom of the front of the box B, I prefer to double said front portion, 85 extending one part b^m in a straight line or even rearwardly, if preferred, to act as a cut-off for the feed, and another portion bⁿ forwardly and downwardly to rest against the bottom near the extreme lower portion thereof 90 and to compel the animal to eat its feed in said lower portion.

In operation the feed is placed within the box through the top thereof and a small portion thereof allowed to roll down into the 95 trough e⁴ by a slight downward pressure upon said trough. The animal commences to eat

5 this food and when the same is nearly exhausted the effort to pick up the remainder causes the animal to exert sufficient downward pressure upon the trough to overcome the force of the spring G and allow more of the feed to roll down. This operation is continued until all of the feed is exhausted. The advantages of the same are twofold. In the first place it is impossible for the animal 10 to get sufficient feed into the open trough to either waste the same or pick it up in too large mouthfuls. Economy in the feed as well as more complete mastication of the same is therefore attained.

15 I recognize the possibility of great variation in form, construction, and arrangement, and I therefore desire to limit myself only as clearly pointed out in the following claims.

20 I claim as new and desire to secure by Letters Patent—

25 1. The combination of the feed-box, B, having its lower portion inclined downward and forward, the bottom, E, hinged to the lower rear portion of the box and extending beyond the front of the same in the form of an open trough, e^4 , the bolt, F, secured in the front, B,

and extending therefrom at an angle through the bottom, E, and bearing below the same the spring, G, and the adjusting-nut, f, adapted to confine the spring between itself and the 30 bottom and both limit the motion of said bottom and regulate the pressure of the spring; substantially as described.

2. The combination with a suitable back, A, of a box, B, having the notches, b^7 , b^8 , in the upper rear portions of its sides and lugs, b^9 , b^x , upon the lower rear portion of said sides, the lid, D, hinged to the box by means of the lugs, d , d' , confined in the notches, b^7 , b^8 , by the back, A, and the bottom, E, yielding 40 pressed against the bottom of the box, said bottom being hinged upon the lugs, b^9 , b^x , by means of hooks, e , e' , opening in a forward direction and held upon the lugs by means of the back, A, said bottom also extending 45 downward and forward in the shape of an open feeding-trough, e^4 ; substantially as described.

HENRY L. FERRIS.
